DESIGN FOR A CARPET

Herbert C. Blomstrom, Springfield, Mass.

Application October 16, 1935, Serial No. 59,085

Term of patent 3½ years

To all whom it may concern:

Be it known that I, Herbert C. Blomstrom, a citizen of the United States of America, residing in Springfield, county of Hampden, and State of Massachusetts, have invented a new, original, and ornamental Design for a Carpet, of which the following is a specification, reference being had to the accompanying drawing, forming part thereof, wherein,

The figure is a plan view of a piece of a carpet showing my new design.

The carpet forming the subject matter of this application is of a single color, the lighter portions of the drawing showing the lighter tones and the darker portions of the drawing showing relatively darker tones.

I claim:

The ornamental design for a carpet, substantially as shown and described.

HERBERT C. BLOMSTROM.
